UNITED STATES PATENT OFFICE

WILLIAM H. GARLAND, OF KANSAS CITY, MISSOURI.

DESIGN FOR A SPOOL-THREAD HOLDER.

SPECIFICATION forming part of Design No. 31,300, dated August 1, 1899.

Application filed June 23, 1899. Serial No. 721,645. Term of patent 7 years.

To all whom it may concern:

Be it known that I, WILLIAM H. GARLAND, of Kansas City, Jackson county, Missouri, have invented and produced a new and original Design for Spool-Thread Holders, of which the following is a full, clear, and exact description, reference being had to the accompanying drawing, forming a part thereof.

This invention relates to a new and useful design for spool-thread holders; and my object is to produce a design for a spool-thread holder which shall be both ornamental and useful.

In the accompanying drawing, which represents a perspective view of a spool-thread holder showing my new design, the leading or material feature resides in the circular series of vertically-slotted cylinders, the post arranged centrally of and projecting upward beyond the top of said series of cylinders, and the scalloped top plate at the top or upper end of said cylinders.

Minor features of the design reside in the keyhole-shaped figure and the central hole-like figure of the top plate having a radial or slot-like extension and in the arm projecting apparently from said post into said slot-like figure; also, in the duplication, on a larger scale, of the series of cylinders, said duplicated set of cylinders being arranged concentrically of and vertically below the first-named cylinders and having their vertical slots arranged in the same radial plane with respect to the center of the post as the vertical slots of the first-named set of cylinders.

Referring to the drawing in detail, 1 designates the circular series of vertical cylinders and 2 the vertical slot-like figures thereof, extending from their lower to their upper ends.

3 designates the vertical post projecting above the top of the cylinders and arranged centrally thereof, and 4 the arm projecting outward from said post.

5 designates the scalloped top plate of the first-named set of cylinders, 7 the central hole-like figure of the top plate through which the post apparently projects, and 8 the slot-like extension of the hole-like figure 7.

9 designates the keyhole-shaped figure of 50 the top plate.

10 designates the duplicate set of circularly-arranged cylinders, this series being of larger size than cylinders 1, and 11 designates the vertical slot-like figures of said 55 duplicate set of cylinders.

12 designates the scalloped top plate of cylinders 10, the upper set of cylinders apparently resting on said top plate.

What I claim is—

The design for a spool-thread holder, substantially as herein shown and described.

In testimony whereof I affix my signature in the presence of two witnesses.

WILLIAM H. GARLAND.
